UNITED STATES PATENT OFFICE.

JOSEPH J. KANE, OF GALVESTON, TEXAS, ASSIGNOR TO KANE BOILER WORKS, OF GALVESTON, TEXAS.

LAND-DREDGING PIPE AND PROCESS OF MANUFACTURE THEREOF.

Application filed February 10, 1927. Serial No. 167,306.

The present invention relates to an improved land dredging pipe, and the process of manufacture thereof.

An important object of the invention resides in the provision of pipe of this nature which has a gradual taper from one end to the other and the smaller end of which has a pronounced taper and has opposed thickened wall portions to compensate for the wear 10 to which these portions are subjected in use.

Another important object of the invention lies in the provision of a pipe of this nature which is formed from a single sheet of metal.

A still further important object of the 15 invention resides in the provision of a pipe of this nature which is simple in its construction, strong and durable, inexpensive to manufacture, thoroughly efficient and reliable in use, easy to couple and uncouple, and 20 otherwise well adapted to the purpose for which it is designed.

Another important object of the invention lies in the process of manufacture of the pipe wherein the smaller end is heated at opposite 25 portions so that said smaller end may be pressed by dies to have a more pronounced taper and will have opposite thickened wall portions.

With the above and numerous other objects in view as will appear as the description proceeds, the invention resides in certain novel details of construction and novel steps of manufacture as will be hereinafter more fully described and claimed.

35 In the drawing:—

Figure 1 is a sectional elevation of a tapered pipe section formed from sheet metal,

40 Figure 2 is a plan view of the sheet from which the pipe section shown in Figure 1 is formed,

Figure 3 is a sectional view showing the smaller end of the tapered pipe section placed between a pair of female dies,

45 Figure 4 is a similar view showing the dies brought together,

Figure 5 is an end elevation of the structure shown in Figure 3,

Figure 6 is an elevation of the finished pipe,

50 Figure 7 is a transverse section therethrough taken substantially on the line 7—7 of Figure 6.

Referring to the drawing in detail, it will be seen that the numeral 5 denotes a sheet of metal from which the pipe is to be formed.

This sheet of metal is cut diagonally along its longitudinal edges to produce a substantially trapezoidal formation and is curved to the tapered tubular formation and welded throughout its length as shown in Figure 6 60 in any suitable manner such as by the process disclosed in my co-pending application filed of even date. I provide a pair of female dies 7 and 8 which may be mounted in a hydraulic or other suitable press structure so that they may be moved towards each other. These dies 7 and 8 are provided with complementary semi-cylindrical recesses 9 that are opposed to each other. Liners 10 have a semi-cylindrical outer surface and a semi- 70 frusto-conical inner surface. The smaller end of the tubular section 6 is heated at those portions confined between dotted lines 10 and 11 shown in Figure 5 and the other portions including the welded seam portions 75 are cold. The smaller end is then placed between the dies 7 and 8 with the seam to one side and the dies are pressed towards each other so that the heated portions between lines 10 and 11 are compressed and 80 become thicker as is clearly illustrated in Figure 7 and the smaller end is formed with a more pronounced taper as is clearly illustrated at 6' in Figure 6. These thickened 85 opposed portions of the end 6' are denoted by numerals 12 and are very important as will be brought out later.

With a plurality of pipe sections constructed in accordance with this invention it will be seen that the smaller end of one pipe 90 section may be inserted in the larger end of another pipe section. These pipe sections are laid with their seams to the side as the greatest wear on these land dredging pipes is at the bottom and particularly at the inner 95 telescoped end at the bottom thereof. The thickened portions 12, of course, resist this wear and cause the pipe to last a comparatively longer length of time in actual use. Obviously, these pipes will be turned around 100 from time to time so as to distribute the wear on both the thickened portions 12. It will also be seen that these pipes are capable of being quickly and easily coupled and uncoupled and may be manufactured at a comparatively low cost.

The utility and advantages of this device and the process for manufacturing the same will be clearly understood, it is thought, by those skilled in this art without a more de- 110

tailed description thereof. The present embodiment of the invention and its process of manufacture have been disclosed in detail merely by way of example since in actual practice they attain the features of advantage enumerated as desirable in the statement of the invention and the above description. It will be apparent that changes in the details of construction and in the steps of the process may be resorted to without departing from the spirit or scope of the invention as hereinafter claimed or sacrificing any of its advantages.

Having thus described my invention, what I claim as new is:—

1. As a new article of manufacture, a pipe comprising an elongated tubular tapered structure having one end smaller than the other, the smaller end having a more pronounced taper than the remaining portions of the pipe, said smaller end being formed with opposed wall sections thicker than the remaining wall sections.

2. As a new article of manufacture, a pipe formed from a single sheet of material bent to form an elongated tubular tapered body the smaller end of which has a more pro-

nounced taper and having a pair of opposed wall sections thicker than the remaining portions thereof.

3. A process of manufacturing pipe sections consisting in placing the smaller end of a tapered pipe section between a pair of female die members having semi-frusto-conical recesses, heating a pair of opposed portions of the smaller end adjacent the centers of the dies and moving the dies towards each other to increase the taper of said smaller end and thicken the heated portions thereof.

4. A process of manufacturing pipe from a tapered tubular member formed from a single sheet of material consisting of heating a pair of opposed portions of the smaller ends of the tubular member a distance from the seam thereof and placing said smaller end in a pair of dies having concave semi-frusto-conical recesses and pressing said smaller end so as to provide it with a more pronounced taper than the remaining portion of the tubular member and to thicken said heated portions.

In testimony whereof I affix my signature.
JOSEPH J. KANE.
